ADJUSTABLE STAND FOR A DRAWING BOARD
OR THE LIKE

David I. Welt, Scarsdale, N. Y.

Application December 28, 1954, Serial No. 33,720

Term of patent 14 years

(Cl. D33—14)

FIG. 1.

FIG. 2.

FIG. 3.

FIG. 4.

Fig. 1 is a front elevational view of an adjustable stand for a drawing board or the like showing my new design.

Figs. 2 and 3 are top plan and left side elevational views, respectively, thereof, and

Fig. 4 is a bottom plan view of the stand shown in Fig. 1 turned at 180°.

I claim:

The ornamental design for an adjustable stand for a drawing board or the like, substantially as shown.
